INVENTOR.

Lewis Pengilly

BY *Henry J. Doherty*
ATTORNEY

UNITED STATES PATENT OFFICE.

LEWIS PENGILLY, OF STOCKTON, CALIFORNIA.

SUCTION VALVE FOR CIGARETTE LIGHTERS.

Application filed January 12, 1924. Serial No. 685,843.

To all whom it may concern:

Be it known that I, LEWIS PENGILLY, a citizen of the United States, residing at Stockton, county of San Joaquin, State of California, have invented certain new and useful Improvements in Suction Valves for Cigarette Lighters; and I do declare the following to be a full, clear, and exact description of the same, reference being had to the accompanying drawings, and to the characters of reference marked thereon, which form a part of this application.

This invention relates to improvements in a suction-control and switch actuating member to be used especially in connection with my cigarette dispenser and lighter, applications for patent on which are copending, the original valve over which the present one is an improvement being particularly shown in application, Serial No. 616,906, filed February 5th, 1923.

The principal object of the present invention is to provide a valve for the purpose to open the suction, close the lighter switch and force the cigarette into engagement with the lighter, arranged to be readily moved to function as above, and which when so moved will remain in such position without further attention or effort on the part of the operator, until an intentional retractive movement is imparted to the valve. The present valve also has less tendency to leak than the previous one.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views:

Fig. 1 is a front elevation of the complete container, dispenser, and lighter, showing my improved suction-valve member in its open position.

Figs. 2 and 3 are sectional views of the valve, showing the same in its closed and open positions respectively.

Fig. 4 is a cross section of the valve on the line 4—4 of Fig. 3.

Referring now more particularly to the characters of reference on the drawings, the

numeral 1 denotes the frame or casing of the device, adapted to be secured onto a dashboard or the like, provided in connection with which are the cigarette containing means 2 and dispensing means actuated by the handle 3, this structure being preferably of the form shown in my copending application for patent on the same filed January 12, 1924, Serial No. 685,884.

Below the containing and dispensing means are horizontal supports 4 for a dispensed cigarette 5. Mounted on the frame 1 on one side thereof in axial alignment with the cigarette on the supports and beyond the same is an electric heating element 6, a lead 7 from which extends to a contact strip 8 mounted on and insulated from the frame adjacent the opposite side thereof.

Fixed on said opposite side of the frame in alignment with the element 6 is a sleeve 9 having a peripheral and diagonally or spirally extending slot 10 of certain length cut therethrough.

A radially disposed passage member 11 taps the sleeve intermediate its ends and in opposed relation to the plane of the slot 10, the outer end of said member being tubular in form and arranged to receive the end of a suction tube 12 thereover.

Mounted in the sleeve 9 with a sliding and turning fit is a cylindrical valve member 13, having at its end facing the element 6 a cup or cone shaped depression 14 adapted to fit over the adjacent end of the cigarette on the supports 4.

Leading inward from said depression is a passage 15 terminating in a peripheral port 15^a intermediate the ends of the valve.

A spring 16 is seated in the member 13 at a point opposite to the port 15^a, said spring 16 pressing against the inner wall of the sleeve 9, and constantly acting to prevent undue freedom of movement of the valve, regardless of wear.

A radial stem 17 forming a handle, is fixed on the valve 13 and projects through the slot 10. The handle and port 15^a are so disposed relative to each other and to the slot 10 and passage 11 respectively that when the handle is at the outer end of said slot, the valve 13 is then telescoped completely in the sleeve 9, and the port 15^a lies to the rear of and above the passage 11. It will therefore be evident that for any air leakage to be had between the

passages 11 and 15, the air would have to traverse a considerable area of the contacting surfaces of the members 9 and 13.

When the handle 17 is drawn to the forward end of the slot, the valve 13 is both advanced and rotated. With its advancement, the adjacent end of the cigarette is engaged by the cup 14 and the cigarette is forced to move longitudinally and into engagement with the element 6. With the rotation of the valve, the port 15 is moved to align with the passage 11, thus opening a continuous passage from the cup 14 to the suction tube 12, the spring 16 then forcing the adjacent surfaces of the sleeve and valve into close contact.

Also with the advancement of the valve, the latter comes into contact with the strip 8 with a good "wiping" action, insuring a good contact being made at all times. This contact causes the heater circuit to be closed.

When the valve has been moved to its last named or operating position, it will remain in such position as long as may be desired, without the necessity of the operator maintaining a grip on the handle.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit

of the invention, as defined by the appended claims.

Having thus described my invention what I claim as new and useful and desire to secure by Letters Patent is:

1. A suction valve member comprising a sleeve, a passage member leading to the periphery thereof, a valve in the sleeve having a peripheral port, said port being normally spaced from the sleeve-passage but adapted to be aligned therewith, means for moving said valve in a manner to cause the port and sleeve passage to be aligned, and spring means between the sleeve and valve to prevent undue freedom of movement of the latter.

2. A suction valve member comprising a sleeve, a passage member leading to the periphery thereof, a valve in the sleeve having a peripheral port, said port being normally spaced from the sleeve-passage but adapted to be aligned therewith, means for moving said valve in a manner to cause the port and sleeve passage to be aligned, and spring means between the sleeve and valve to prevent undue freedom of movement of the latter, and also acting, when said port and passage are aligned, to force the adjacent surfaces of the sleeve and valve which surround said port and passage into close contact.

In testimony whereof I affix my signature.

LEWIS PENGILLY.
